UNITED STATES PATENT OFFICE.

MAX GARBELL, OF CHICAGO, ILLINOIS.

MULTICOLORED-RIBBON SHIFT FOR TYPEWRITERS.

Application filed January 19, 1920. Serial No. 352,514.

To all whom it may concern:

Be it known that I, MAX GARBELL, a citizen of the United States, residing at Chicago, in the county of Cook and State of Illinois, have invented certain new and useful Improvements in a Multicolored-Ribbon Shift for Typewriters, of which the following is a specification.

This invention relates to improvements in a ribbon shifting mechanism for typewriting machine of that type of such machines in which reciprocating type bars are employed, and in that kind of ribbon shifting mechanism used for shifting a plural or bicolored ribbon so that the proper colored portion thereof may be correctly positioned between the typed ends of the type carrying bars and platen of the machine, to produce impressions of the desired color on the paper being used, and it consists in certain peculiarities of the construction, novel arrangement, combination and operation of the various parts thereof as will be herein-after more fully set forth and specifically claimed.

One of the objects of the invention is to provide a ribbon shifting mechanism which shall be so constructed, arranged and operatively connected to the carriage supporting frame of the typewriting machine as to be carried thereby and therewith in its movements, to the end, that when the carriage is shifted, the ribbon will be positioned and so held as to cause one of the colors to be typed, until it is shifted or "set" independently of the movement of the carriage.

Another and important object is to provide the mechanism with ribbon holding means of such construction, arrangement and operation of its parts, as to limit its movement in opposite directions, or forwardly and rearwardly, thereby preventing the ribbon holding means or fingers striking or contacting with the paper on the platen and thus causing carbon marks.

A further object is, to furnish a device of the above named general character, which shall be simple and inexpensive in construction, reliable and efficient in action, strong and durable.

Other objects and advantages of the invention will be disclosed in the following explanation and description.

In the accompanying drawings, which serve to illustrate an embodiment of the invention—

Fig. 1 is a view partly in elevation and partly in vertical section of a portion of the carriage frame, a part of the type bar frame or guide, and the platen of a typewriter showing my improvements mounted on the carriage frame and by continuous lines the position the parts of the mechanism will occupy, with one of the colored portions of the ribbon positioned for use, and by dotted lines the position of the parts when the other colored portion of the ribbon is so positioned.

Fig. 2 is a fragmental sectional view taken on line 2—2 of Fig. 4 looking in the direction indicated by the arrows.

Fig. 3 is a plan view taken on line 3—3 as indicated by arrows in Fig. 1.

Fig. 4 is a fragmental face view of a portion of the carriage frame showing the ribbon shifting mechanism mounted thereon and illustrating a fragment of a two-colored ribbon held thereby.

Fig. 5 is an end elevation of portions of the carriage frame, and

Fig. 6 is a cross-sectional view thereof taken on line 6—6 of Fig. 4 looking in the direction indicated by the arrows.

Corresponding numerals of reference designate similar parts throughout the different views of the drawings.

The reference numeral 10 designates one of the end pieces or plates of the carriage of the machine which may be connected to the other plate thereof between which the platen 11 is journaled by means of a rod 12 and shafts 13 and 14, and also by means of carriage rails 15 which are mounted on anti-friction ball bearings 16 supported by the carriage rail supports 17 in the usual or well-known way. These supports are mounted on the upper portion of end pieces 18 of the carriage supporting frame and in parallelism with the rails 15 but below the same so as to provide races or tracks for the ball bearings 16 on which the rails 15 rest. Each of the end pieces 18 is provided on its rear portion with rearwardly extended arms 19 located one above the other and each of said arms has journaled thereon a pair of rollers 20 to co-act with a vertical guide 21 on the rear portion of the main frame 22 of the machine, a portion of the side walls of said frame being shown by dotted lines in Fig. 1 of the drawings.

At least one of the end pieces 18 of the carriage supporting frame has pivotally

connected thereto one end of a lever 23 which is suitably fulcrumed on the main frame and is used for vertically shifting the position of the carriage supporting the frame, as well as, the carriage thereon. That end of the lever 23 attached to the end piece 18 is provided with an elongated opening 24 through which is extended a pin 25, which arrangement will permit of the proper movements of said lever and frame, as is obvious.

Extended forwardly, and by preference, horizontally from the lower portion of the front support 17, are a pair of apertured brackets 26, one of which is located near one end of the said support or bar 17 and the other at a suitable distance therefrom. Journaled at one of its ends on one of the brackets 26 is a rock-bar 27, the other end of which is mounted for rotation on the end of an adjusting screw 28 located in the opening of the bracket 26 near the end of the support 17 as is clearly shown in Figs. 3 and 4, of the drawings. The bar 27 has near its outer end a shifting or operating handle or lever 29 and near its other end a pair of spaced apart arms 30, all of which extend forwardly, and normally in a downward direction. Each of the arms 30 has on its outer portion an apertured ear 31, to each of which is pivotally secured the lower end of a ribbon holder or finger, each designated as a whole by the numeral 32. Extended forwardly and horizontally from the upper portion of the front support 17 outwardly of or near the fingers 32 is a pair of arms 33 each of which has an inward extension 34 to co-act with the fingers 32 to restrict their movements in opposite directions.

As is clearly shown in Figs. 1 and 2, each of the fingers 32 is provided at its lower portion with a rearwardly extended loop 35 which provides a vertically elongated opening 36, in which one of the extensions 34 is located, which arrangement will permit of free vertical movement of the fingers, but as the extensions 34 will contact with the walls of said openings therein, their back and forth movements will be restricted. The upper portion of each of the fingers 32 is provided with a vertically and transversely disposed ribbon receiving slot 37 in which the ribbon 38 of a plural or two color type, for example, of black 39 and red 40 sections, see Fig. 4, may be readily placed through an opening 41 leading to each of said slots and thereby properly held and guided between the type carrying bars and platen.

The handle 29, which is by preference integral with the rock-bar 27 is provided with a downwardly extended flange 42, see Figs. 3 to 6, which has in its lower edge a plurality of recesses 43 for alternate en-

gagement with a ball 44 supported or pressed by a spring 45 mounted on the front supports or rails 17 and extended forwardly therefrom. The front lower portion of each of the fingers 32 has affixed thereto one end of a spring 46 which is extended around the pivot on which its finger is mounted and connected at its other end to the arm 30 adjacent thereto, thus holding said fingers in their normal positions as shown by continuous lines in Figs. 1 and 2 of the drawings.

Suitably mounted in front of the platen 11 is the base 47 of the frame or support of the reciprocating bars 48, each of which has mounted on an upright member 49 thereof, type 50, 51 and 52, which are arranged one above the other as shown, and usually with the small letters or type 50 in the lowermost position, the figures or characters 52 in the uppermost position and the capital letters or type 51 in an intervening position. These bars may be reciprocated in the ordinary or any well known way. The base 47 has on its rear portion upright standards 53 which carry at their upper ends a rearwardly directed guide 54 for the members 49 and rearwardly of said upright an extension 55 which is provided with a guide 56 for the lower portions of the bars 48 or members 49 thereof to direct the type on said bars to a unitary or common striking point on the platen.

From the above it will be understood that the guides 54 and 56 are located between but rearwardly of the standards 53 of the type-bar carrying frame.

Assuming that the parts are in the positions shown by full lines in Fig. 1, it will be understood that the ribbon 38 will be held substantially taut and in position for the colored section 39 thereof to be struck by the type 50, which operation will cause the ribbon and its fingers to be deflected rearwardly to about the position shown by dotted lines in Fig. 2, for each stroke of the type bars, the springs 46 yielding sufficiently for this purpose, but exerting their tension, when the ribbon is freed, against the fingers so as to restore to and hold them in their normal positions. In the above mentioned rearward movement of the fingers it is manifest that the extensions 34 on the arms 33 will contact with the front walls of the openings 36 of the fingers thus preventing the latter striking the paper on the platen which would cause carbon marks thereon when carbon paper is used.

If it is desired to write with the small type or letters 50 in another color, the ribbon holders or fingers can be shifted or moved upwardly by raising the lever 29 to about the positions of said parts shown by dotted lines in Fig. 1 of the drawings, when it is obvious that the colored section 40 of

the ribbon will be properly positioned for receiving the impact of said letters or type, and also, that the thus shifted ribbon and its holders will be so maintained by reason 5 of the engagement of the spring actuated ball 44 with the recess 43 in the flange 42 of the lever 29 adjacent to the front rail 17 of the carriage supporting frame.

By my improvements it is apparent that 10 by depressing the carriage shifting lever 23, the carriage and the ribbon shifting and holding mechanism will be moved at the same time, but that the ribbon may be shifted independently of the movement of 15 the carriage and its supporting frame.

Having thus fully described my invention, what I claim as new and desire to secure by Letters Patent is—

1. In a mechanism of the class described, 20 the combination with a carriage-supporting frame mounted for vertical movement; of a platen-carrying carriage mounted on said frame; a rock bar journaled on the front portion of said supporting frame and having 25 a pair of spaced-apart forwardly extending arms and near one of its ends an operating lever; a pair of spaced-apart spring-actuated ribbon-holding members pivotally mounted on said arms and extended in front 30 of the platen, each of said members having in its lower portion an elongated opening; a pair of arms extended forwardly from the upper portion of said supporting frame and each having a lateral extension located in 35 the opening of the ribbon-holding member; and means engaging the rock bar to retain it in a given position.

2. A machine of the class described including, in combination: a carriage-supporting frame mounted for vertical movement; a rock bar journaled on the front portion of said frame and having a pair of spaced-apart forwardly extending arms and near one of its ends an operating lever, said lever 45 having a recessed flange extending therefrom; a spring mounted on said supporting frame and extended near the recessed portion of said flange; a ball located between said spring and the recessed portion of said 50 flange; a pair of spaced-apart ribbon-holding members pivotally mounted on said members and extended upwardly therefrom; springs, each attached at one of its ends to the lower front portion of one of said members and extended around the pivot thereof 55 and applied at its other end to one of said arms; and a pair of arms extended forwardly from the upper portion of said supporting frame and cooperating with said 60 members to restrict the rearward movement of said members.

3. In a multi-colored ribbon shift for

typewriters having a carriage-supporting frame adapted for vertical movement and a platen carriage mounted on said frame, the 65 combination with ribbon-holding and guiding means extended in front of the platen and oscillatably mounted on the carriage-supporting frame to swing about an axis parallel to the platen toward and from the 70 latter; of resilient means supported entirely from said frame for yieldingly resisting movement of said ribbon-holding means toward the platen and for automatically restoring said holding means to normal position after a printing operation; and manually operable means mounted on said frame and cooperable with the ribbon-holding means for adjusting the latter vertically 75 relatively to the frame to thereby bring different portions of the ribbon into operative position for printing.

4. In a multi-colored ribbon shift for typewriters having a carriage-supporting frame arranged for vertical movement and 85 a platen carriage on the frame, the combination with transversely spaced ribbon-holding and guiding members extended in front of the platen; of a shaft supported from said frame and extending parallel to 90 the platen and upon which said members are pivotally mounted; means for adjusting the angular position of said shaft to thereby vary the vertical position of the ribbon-holding members with respect to the frame and 95 the platen; means rigid with said frame and cooperable with said members to limit the pivotal movements of the latter toward and from the platen; and means for restoring said ribbon-holding members automatically 100 to normal position after each printing operation.

5. In a multi-colored ribbon shift for typewriters having a carriage-supporting frame arranged for vertical movement and 105 a platen carriage on the frame, the combination with a rock shaft mounted on said frame and extending parallel to the platen, said shaft having forwardly extended arms; of a pair of ribbon-holding and guiding members pivotally mounted at their lower ends 110 on said arms; springs interposed between said members and said arms to yieldingly resist pivotal movement of said members on said arms and restore said members to normal position; detent means mounted on said frame and cooperable with said rock shaft to retain the latter in different adjusted positions; and means cooperable with said 115 ribbon-holding members to limit the amount of pivotal movement thereof with respect to the arms of said rock shaft.

MAX GARBELL.
